Primary Examiner — George D. Kirschbaum*Assistant Examiner* — Joseph J Kukella(74) *Attorney, Agent, or Firm* — Tarolli, Sundheim, Covell & Tummino LLP; John A. Yirga, Esq.(57) **CLAIM**

The ornamental design for a golf tee, as shown and described.

DESCRIPTION

FIG. 1.1 is a front elevation view of a golf tee as illustrated in our ornamental design;

FIG. 1.2 is a left side elevation view thereof;

FIG. 1.3 is a rear elevation view thereof;

FIG. 1.4 is a top front perspective view thereof; and

FIG. 1.5 is a bottom perspective view thereof.

The undulating line crossing the cylindrical neck of the golf tee illustrates a symbolic break in its length. The appearance of any portion of the article between the portions of the golf
